REFRIGERATOR CABINET

Montgomery Ferar, Huntington Woods, and Richard E. Hitchcock and Charles R. Russell, Southfield, Mich., assignors to Whirlpool Corporation, a corporation of Delaware

Filed May 24, 1963, Ser. No. 75,217

Term of patent 14 years

(Cl. D67—3)

The dominant features of our design reside in the portions in full lines, said features being characterized by the handle portion having the configuration as shown.

We claim:

The ornamental design for a refrigerator cabinet substantially as shown and described.
